SULFURIC ACID FORTIFICATION IN
ISOPARAFFIN ALKYLATION

Arthur R. Goldsby, Beacon, and Claude W. Watson, Eastchester, N. Y., assignors to The Texas Company, New York, N. Y., a corporation of Delaware

Application January 23, 1945, Serial No. 574,137

5 Claims. (Cl. 260—683.4)

1

This invention relates to sulfuric acid alkylation of an isoparaffin with an alkylating agent, such as an olefin, for the production of gasoline hydrocarbons of high antiknock value suitable for aviation gasoline and motor fuel.

One of the principal objects of the invention is to provide a novel process to improve the quality and yield of the alkylate and to improve acid life.

Another object of the invention is to continuously maintain the water content of the system acid below 4% by weight, and preferably below about 1% by weight, in a novel and economical manner in order to achieve the foregoing results.

Still another object of the invention is to provide for the continuous fortification of acid recycled in the process with SO_3 or fuming H_2SO_4 in accordance with the water content of the recycle acid stream and under conditions to prevent reaction with carbonaceous material in the acid and avoid other deleterious results.

A further object of the invention is to provide a multistage alkylation system having series flow of isoparaffin and also preferably acid catalyst, and split feed of olefin, with continuous fortification of the recycle acid with fuming acid and return of the resulting fortified acid to the multistage system in a manner to maintain the water content of the system acid throughout the multiple stages at the low level specified above.

An additional object of the invention is to provide a novel method in continuous sulfuric acid alkylation, with continuous discharge of a portion of the system acid to recovery and recycle of the balance together with makeup and/or fortifying acid, whereby the organic content of the system acid is maintained substantially above that heretofore employed, while concomitantly maintaining the water content of said system acid substantially below that heretofore obtainable.

Other objects and advantages of the present invention will be apparent from the following description when taken in connection with the accompanying drawing and appended claims.

In the continuous sulfuric acid isoparaffin-olefin alkylation process, it has been specified that the titratable acidity of the system acid should be maintained above about 90% for C_4 olefins and above about 87% for C_5 olefins, where strong makeup acid of about 98% strength is employed. However, only recently has it been recognized that the water content of the system acid is a major contributing factor to deleterious results on the quality and yield of the aviation fraction, and on acid life, when that water content builds

2

up in continuous operation. Predrying of the hydrocarbon feed to the alkylation reaction zone has been proposed in an effort to eliminate objectionable water dilution in the system. It has now been discovered that this procedure, while helpful, is not a complete solution of the problem. Water is synthesized in the alkylation process as a result of side or secondary reactions which cannot be effectively suppressed, and this 10 serves to build up the water content of the system acid in continuous operation to an objectionable level in conventional alkylation units operating with acid recycle, even where predrying of the hydrocarbon feed is employed.

15 The present invention is predicated on the discovery that the water buildup in the system acid, by virtue of water synthesized in the alkylation process, should be continuously removed to maintain the water content of the system acid below 20 4% by weight and preferably below about 1% by weight. This is accomplished in accordance with the present invention by continuously fortifying the recycle acid stream with SO_3 or fuming H_2SO_4 . While the use of fuming acid as makeup in sulfuric acid alkylation has heretofore been suggested, this has never become commercial practice because of difficulties encountered in its use that were considered inherent and unavoidable. It is generally recognized that the presence of 25 30 free SO_3 in the alkylation acid is objectionable and should be avoided.

While the prior suggestions to employ fuming acid as makeup failed to correlate the amount and strength of the added fuming acid with 35 the water content of the system acid, so that free SO_3 may have been present in the resulting fortified acid, this is not the sole cause of the difficulties previously experienced. The addition of fuming acid to a stream of recycle acid containing 40 an appreciable proportion of water liberates substantial heat as a result of reaction and dilution. Consequently, when the addition is carried out on recycle acid at ordinary temperature as it is conventionally returned from the settler, 45 or even at a somewhat reduced temperature due to chilling or evaporative cooling in the reaction zone and/or settler, nevertheless the heat liberated is sufficient to raise the temperature of the fortified acid stream substantially above 40° F. 50 This has resulted in rapid attack of the SO_3 or fuming acid on the organic material present in the recycle acid, with the formation of a tarry viscous black liquid which is unsatisfactory for the alkylation reaction, necessitating the dumping 55 of the acid so treated.

It has now been discovered that, when the recycle acid stream containing both organic matter and water is prechilled to a temperature substantially below 40° F., such as about 20-30° F., the required amount of fuming acid to react with substantially the entire water content of recycle acid containing less than about 10% water by weight can be added with efficient mixing and without raising the temperature of the mixture above 40° F.; and at these low temperatures of about 40° F. and below, the fuming acid preferentially reacts with the water and does not deleteriously attack the organic content of the recycle acid in the short time required to complete the reaction of free SO₃ with the water and thus remove free SO₃ from the resulting mixture.

In accordance with the present invention, the recycle acid stream is prechilled, fuming acid is added to the prechilled recycle stream with good agitation to avoid localized reaction and overheating, the amount and strength of the fuming acid is controlled in accordance with the water content of the recycle acid stream to reduce that water content to a low value of the order of less than 2% and preferably less than 1%, such as about 0.25-0.75%, while at the same time the presence of free SO₃ in the resulting fortified recycle stream is avoided, and the temperature of prechilling of the recycle acid stream is controlled so that the heat liberated on addition of the fuming acid to the recycle acid stream does not raise the temperature of the mixture above 40° F. The amount of chilling required is dependent on the water content of the recycle acid and the initial temperature of the latter. The resulting fortified and chilled recycle acid stream is then returned to the alkylation reaction zone in an amount to maintain the water content of the system acid therein below 4% by weight and preferably below 1% by weight. Preferably, the fortified and chilled recycle acid stream is first thoroughly mixed with isoparaffin, either feed or recycle isoparaffin or both, and the resulting mixture then passed to the alkylation reaction zone.

In continuous operation, where a substantial amount of acid is continuously recycled in the system, the amount of fuming acid required to control the water content may also supply the required makeup H₂SO₄ to prevent buildup of organic matter in the system acid above a predetermined maximum. It is obvious that a more dilute fuming H₂SO₄, such as one containing 8% free SO₃, will add more H₂SO₄ per unit amount of free SO₃ than say a fuming acid containing 20% free SO₃. While SO₃ itself can be employed to control the water content, as a matter of convenience it is generally preferred to use fuming acid; and the strength of the fuming acid available in the supply tanks and feed pipes is selected in accordance with the freezing or congealing point to avoid solidification in the lines at normal atmospheric temperatures encountered. For these reasons, a supply of fuming acid containing about 20% free SO₃ is generally used; and, if desired, this may be diluted with H₂SO₄ to reduce the free SO₃ content at or just prior to mixing with the recycle acid stream.

Where the amount of H₂SO₄ added in the fuming acid, in which the free SO₃ is proportioned in accordance with the water content of the recycle acid stream, is insufficient to supply the required makeup H₂SO₄ to maintain the required acid to hydrocarbon ratio in the system, then additional acid of low or close to zero water content and devoid of free SO₃ is also added during continuous

operation. For example, it may be necessary to increase the proportion of settled acid discharged to recovery in order to prevent organic buildup in the system acid above a predetermined maximum as more particularly described hereinbelow; and the amount and strength of fuming acid added in accordance with the water content of the recycle acid stream may be such that the rate of withdrawal of settled acid from the system exceeds the rate of addition of H₂SO₄ in the fuming acid. This would reduce the acid to hydrocarbon ratio in the system with continued operation; and additional makeup acid of as near zero water content as is readily available and which is devoid of free SO₃ is then added to compensate for the excess amount of acid discharged to recovery and thereby maintain the acid to hydrocarbon ratio in the system.

Preferably, 99.5-100% H₂SO₄ on an organic-free and ash-free basis is employed as such additional makeup, where that strength of acid is conveniently and economically available. In such case, the said 99.5-100% makeup acid may be added at any place in the system following the settler or even directly to the alkylation reactor; but preferably this makeup acid is added either to the fuming acid stream or to the isobutane recycle stream so as to be thoroughly mixed with the prechilled and fortified recycle acid prior to introduction into the alkylation reactor. Ordinarily, a strength of acid less than 96% H₂SO₄ on an organic-free and ash-free basis will not be employed for makeup, to thereby avoid adding objectionable quantities of water to the system.

It will be understood that the strength of the makeup H₂SO₄ is expressed on an organic-free and ash-free basis, so that the balance between the expressed strength of the acid and 100% consists essentially of water.

40 "White" acid, as the term implies, is substantially free of organic content. However, this white acid may contain some dissolved mineral matter or inorganic salts, such as lead sulfate, ferric sulfate, etc. Small amounts of this dissolved mineral matter up to about 3-4% or somewhat higher, expressed as ash content by weight, can be present in the makeup acid without deleterious results. Consequently, the titratable acidity of the makeup white acid is expressed on an ash-free basis to show water content, although it will be understood that the ash content of such acid is generally small. "Black" acid on the other hand contains organic or carbonaceous matter in addition to water and some dissolved mineral matter. Ordinarily, the organic content of strong black acid will run about 1-5% with a water content of about 1-4% and an ash content of about 0.5-1.5%. As described in greater detail hereinbelow, the organic content of makeup black acid is definitely not objectionable and may even be advantageous in this alkylation reaction, so long as organic buildup in the system acid above a predetermined maximum is avoided. The titratable acidity of makeup black acid is expressed on an organic-free and ash-free basis to show water content, since the latter is the critical or objectionable constituent of the makeup acid. Whenever the expressions "99.5-100% H₂SO₄" and "96-99.5% H₂SO₄" are used in the following description and claims as referring to makeup acid, it will be understood that this is on an organic-free and ash-free basis. Consequently, "99.5-100% H₂SO₄" means a makeup sulfuric acid having 0.5-0.0% water; and "96-99.5% H₂SO₄" means 70 a makeup sulfuric acid having 4.0-0.5% water.

On the other hand, where titratable acidity of the system acid, that is, the acid present in the alkylation system including the reactor and settler, is mentioned in the following description and claims, it will be understood that this means the measured acidity or H_2SO_4 by titration which will be less than 100% by the combined amounts of water, organic material and mineral matter which are present therein.

Preferably, the makeup white or black acid has a titratable acidity on an organic-free and ash-free basis of at least 98% to avoid water dilution; and the ash content of said make-up acid generally runs about 0.0-1.5%, although it may be somewhat higher without objection. The organic content of makeup black acid is maintained below 10% so that organic buildup in the system acid above about 20% is prevented. Where the available makeup acid contains in excess of 1/2% water, thus having a titratable acidity on an organic-free and ash-free basis of 96-99.5% H_2SO_4 and preferably 98-99.5% H_2SO_4 , this makeup acid of appreciable water content is added to the recycle acid stream in advance of the chiller. And the amount and strength of added fuming acid is then proportioned to compensate for the water introduced with the makeup acid as well as the water present in the recycle acid. It will be understood that the fuming acid is prepared from white acid substantially free from organic content, to avoid attack of the SO_3 on carbonaceous material of black acid.

The present invention is more particularly illustrated in the attached drawing disclosing preferred embodiments thereof and wherein

Fig. 1 is a diagrammatic view of a single stage alkylation unit incorporating the principles of the present invention; and

Fig. 2 is a diagrammatic view of a multistage alkylation unit having serial flow of isoparaffin and preferably acid, and split feed of olefin, and incorporating the features of the present invention.

Referring to Fig. 1, feed isobutane from line 10, after passing through a suitable drier 11, is introduced by valve-controlled line 12 into the recycle line 13 containing the recycle acid and recycle isobutane as hereinafter described. This mixture is introduced into the alkylation reactor 14, which may be of any conventional or suitable type, such as a pump and time tank reactor, jet reactor, impeller type reactor and the like. The olefin feed, which may be a C_4 refinery cracked gas fraction, is passed by line 16 through a suitable drier 17 and thence into the alkylation reactor 14. If desired, a portion or all of the isobutane feed from line 12 can be by-passed by valve controlled line 18 for mixing with the olefin feed in line 16 to thereby adjust the isobutane to olefin ratio, such as to produce in excess of about a 1:1 molar ratio, in the olefin feed line. It will be understood that the olefin feed supplied to line 16 has preferably been caustic-washed and then water-washed. While predrying of the hydrocarbon feed as disclosed is the preferred procedure, it is to be understood that this is not essential in accordance with the present invention, since sufficient fuming acid can be added to also compensate for water added with the feed.

Alkylation reaction products are discharged 70 from reactor 14 by line 20 and introduced into settler 21. Here separate hydrocarbon and acid phases are formed, and the separated hydrocarbon phase is removed by line 22 for passage to suitable caustic washing and water washing 75

equipment and then to stabilizing and fractionating towers in conventional manner. The settled acid layer is continuously removed by bottom line 23, a position thereof being discharged to recovery by valve-controlled line 24, and a substantial proportion, usually a major proportion, diverted into the valve controlled acid recycle line 25. Preferably, the settler 21 is operated with a minimum acid level indicated at 26 by sufficiently rapid withdrawal of the settled acid from settler 21 to maintain the level of flat acid in the settler at the lowest point consistent with proper operation of the usual automatic controls.

15 The recycle acid stream passes to a suitable chiller 28 where the temperature is reduced substantially below 40° F., ordinarily to around 25-30° F. The chilled recycle acid then flows through line 29 into which is introduced by line 30 SO_3 or fuming H_2SO_4 . For a convenience in description, the expressions "fuming acid" or "fuming H_2SO_4 " are hereinafter employed in the description and claims to include SO_3 as well as H_2SO_4 in which SO_3 has been absorbed to produce fuming acid. As stated above, the fortifying SO_3 is most conveniently applied in the form of SO_3 absorbed in sulfuric acid; and the fuming acid strength is generally selected to provide for low freezing or congealing point. Consequently, the material supplied by line 30 will generally be fuming acid containing about 20% free SO_3 . The amount and strength of the fuming acid added by line 30 is controlled in accordance with the water content of the recycle acid stream passing through line 29. This is conveniently accomplished by regularly sampling acid withdrawn at 24 and making a water determination thereon. It will be understood that line 29 will be equipped with a suitable flow meter, so that the amount of free SO_3 required to react with and reduce the H_2O content of the recycle acid can readily be computed from the velocity of flow of the recycle acid through line 29 and the mentioned water determination on that acid.

40 45 The resulting mixture is immediately passed through a suitable mixer 32, such as a baffled compartment providing turbulent flow, to insure that the reaction between the free SO_3 and the water of the recycle acid is rapidly completed without local overheating and a homogeneous mixture devoid of free SO_3 discharged by line 33. If desired, mixer 32 can also be provided with heat exchange coils or jacket for the circulation of refrigerant or other cooling medium to assist in maintaining the desired low temperature of the mixture. In some cases, where the water content of the recycle acid is high, the pre-chilling required to prevent objectionable rise of temperature on addition of fuming acid may be such as to lower the temperature of the recycle stream in chiller 28 to the point where the viscosity of the chilled recycle stream becomes unduly high, such as to render it difficult to pump the stream and secure proper turbulent flow and mixing of that stream with the fuming acid. 50 55 60 65 The presence of a substantial soluble organic content in the acid recycle stream lowers the freezing or congealing point; and ordinarily pre-chilling of that stream as low as about 20° F. can be accomplished without difficulty. However, in those cases where the equilibrium conditions of the continuous system would encounter viscosity difficulty on prechilling of the acid recycle stream to the required low temperature to properly absorb the heat of reaction and di-

lution upon addition at one point of the total amount of fuming acid to reduce the water content to the desired low figure, then the fuming acid is added to the recycle acid stream in stages with intercoolers between the stages. Thus, the recycle acid is first prechilled to a temperature above that at which the viscosity increases unduly, a portion of the fuming acid is then added and thoroughly mixed with the stream and the latter is again refrigerated, as by the use of a separate mixer followed by an intercooler or by the use of a combined mixer and intercooler, additional fuming acid is then added, and the process repeated in the required number of stages to reduce the water content to the desired low figure while at the same time preventing local overheating and maintaining the temperature of the mixture below 40° F. The water content of the resulting mixture discharged by line 33 is less than 2% by weight and preferably less than 1%, and may be of the order of about 1/4-3/4%, and usually about 1/2%. This is to insure that no free SO₃ remains in the recycle acid introduced into the reactor 14, thereby avoiding prolonged contact and resulting reaction of free SO₃ with the organic content of the system acid. At the same time, the water content of the recycle acid is thereby continuously reduced to such a low figure that the system acid in reactor 14 is maintained at a water content below 4% by weight and preferably below 1%. The chilling of the recycle acid stream in chiller 28, or in chiller 28 coupled with mixer cooling or one or more intercoolers as described above, is controlled so that the temperature of the mixed recycle acid and fuming acid does not rise above 40° F. This can be accomplished in any suitable manner, such as by regulating the supply of refrigerant to each chiller, or by the use of a valve-controlled by-pass around each chiller.

The resulting fortified and chilled acid recycle stream is mixed in line 33 with isobutane recycle from line 35. It will be understood that the hydrocarbon phase removed by line 22, after being caustic-washed and water-washed, is then passed to the conventional stabilizer or debutanizer, where normal butane and lighter is removed overhead. The resulting off-gases are then passed to the conventional butane fractionator, where isobutane and lighter is removed overhead and normal butane discharged as bottoms. The isobutane and lighter overhead may then be depropanized, thereby providing a purified and concentrated isobutane stream which is recycled to line 35. The resulting mixture of isobutane recycle and fortified acid recycle is thoroughly mixed in a suitable baffled compartment or mixer 36, and returned by line 13 together with feed isobutane from line 12 to the reactor 14.

Where SO₃ is introduced by line 30, or in any event where the H₂SO₄ containing absorbed SO₃ supplied by line 30 is insufficient to provide the required makeup acid to compensate for that discharged to recovery by line 24, additional acid which is devoid of free SO₃ and which contains as low a water content as practicable, is introduced into the system by either valve-controlled line 38 or valve-controlled line 39. Where 70 99.5-100% H₂SO₄ is available for makeup, then it is added by line 38 through either valve-controlled branch line 40 into the fuming acid line 30, or through valve-controlled branch line 41 into the isobutane recycle line 35. Where the 75 amount of isobutane recycle to be materially re-

available makeup acid contains in excess of 0.5% H₂O, such as 96-99.5% H₂SO₄, then this makeup acid is added by line 39 to the acid recycle line 25 in advance of chiller 28. In the latter case it will be seen that the recycle acid plus the makeup acid of appreciable water content are thus passed through chiller 28; and the amount of fuming acid added by line 30 is then proportioned to compensate for the water content of the combined recycle acid and makeup acid, so that the resulting fortified acid of line 33 has a low water content of the order specified above.

Fig. 2 discloses a five-stage concurrent flow unit with split feed of olefin of the character disclosed and claimed in the copending application of Arthur R. Goldsby and Claude W. Watson Serial No. 574,136, filed of even date herewith. As shown, feed isobutane from line 45 passes through drier 46 and thence is introduced by valve-controlled line 47 into the recycle line 48 containing fortified recycle acid mixed with recycle isobutane. This mixture is introduced into the first stage 50 of the multistage alkylation unit having the five reactors 50-54 of the eccentric rotor type, although other conventional types of contactors can be employed. Olefin feed from line 55 passes through drier 56 and thence is split by the valve-controlled branch lines 57-61 between the reactors 50-54 of the multistage unit. If desired, a portion or all of the isobutane feed from line 45 can be introduced by the valve-controlled branch line 62 into the olefin feed line 55 to raise the isobutane to olefin ratio of this olefin feed.

Each of the branch lines 57-61 constitutes a manifold supplying a large number of pipes or nozzles indicated at 63 which serve to introduce the olefin feed into each reactor by "multipoint" olefin addition. It will be understood that this means the introduction of the olefin into the agitated or circulated stream of hydrocarbon or catalyst in finely divided form and at a large number of spaced points extending throughout a substantial portion of the volume of the mechanically agitated mix in each reactor. By combining the feature of fine subdivision of the olefin with the finite spacing of the substantial number of points of olefin introduction, so as to prevent any substantial accumulation or buildup of olefin in any increment of the acid in the reaction mixture, as disclosed and claimed in our copending application Serial No. 476,896 filed February 24, 1943, local overheating and alkyl ester buildup in the acid catalyst are prevented, and objectionable side reactions are minimized.

It will be noted that in the preferred arrangement, the bulk of the isobutane and acid are introduced by line 48 into the first stage 50 to flow serially through the system, along with alkylate produced in each stage, by means of the connecting lines 64-67. This means that the highest isobutane concentration in the hydrocarbon phase of the reaction mix will be found in stage 1; and the isobutane concentration is progressively reduced from stage to stage throughout the system. The amount of olefin injected by multipoint addition in each stage is preferably regulated in accordance with the isobutane concentration in that stage whereby the amount is progressively reduced from the first to the last stage of the system. In this manner, a superior quality of alkylate can be produced in high capacity with a lower overall isobutane requirement for the system, thereby enabling the amount of isobutane recycle to be materially re-

duced with resultant economy in installation and operating expense.

The present invention involving the maintenance of the water content of the system acid at a low value below 4% by weight and preferably below 1% by weight further contributes to the improvement in alkylate quality and yield of aviation fraction, as well as catalyst life. As shown, reaction products overflow from the last stage 54 by line 69 to settler 70, where stratification occurs into a hydrocarbon layer, which is removed by line 71 to the above-described neutralizing, washing and fractionating equipment, and an acid layer indicated at 72 which is removed by bottom line 73. A regulated portion of the acid from line 73 is discharged to recovery by line 74, and the balance is recycled by line 75 through chiller 76 to line 77. Fuming acid is introduced at this point by line 78 in accordance with the water content of the recycle acid stream, and the mixture flows through mixer 79 where reaction of free SO₃ with the water content and dilution to a homogeneous composition are completed.

The resulting fortified and chilled stream then passes by line 80, together with isobutane recycle from line 81, through mixer 82 to line 48 for return to the first stage 50 of the alkylation system. As shown, any makeup 99.5-100% H₂SO₄ is added by line 84 to line 48 to be introduced into the first stage of the system. This is of particular application to a modified operation in which a portion of the fortified recycle acid, either unmixed or mixed with a portion of the isobutane recycle, is split between the stages as described hereinbelow. Where substantially all of the recycle acid and isobutane recycle are introduced into the first stage, the strong makeup acid can of course be introduced into the line at any point as described above in connection with Fig. 1. Weaker makeup acid, such as 96-99.5% H₂SO₄, is introduced by line 85 into the recycle line 75 in advance of chiller 76 as described in connection with Fig. 1.

As an alternative procedure, a portion of the fortified recycle acid can be passed by valve-controlled line 87 to manifold 88 and distributed by valve-controlled branch line 89-92 between stages 2-5 of the alkylation system, the balance passing together with isobutane recycle from line 81 through mixer 82 and thence by line 48 to the first stage 50. This provides for independent control of the catalyst to hydrocarbon ratio in the individual stages, and also permits independent control of the water content of the system acid in each stage. Thus, the catalyst to hydrocarbon ratio may be progressively varied or reduced from stage to stage. For example, the reaction mix in the first stage operating with the highest acid loading rate (volume of olefin added per volume of catalyst per hour) may contain about 65-75% acid by volume; and this ratio may be progressively reduced in succeeding stages until in the final stage, operating with the lowest acid loading rate, the acid content of the reaction mix may be approximately 50% by volume.

In addition, the various stages may be operated with catalyst holdup, such as by the provision of reactors in which partial settling is permitted in the upper portion or space from which the emulsion stream is overflowed or discharged to the next stage in series, whereby hydrocarbon-enriched emulsion thus passes from stage to stage and a substantial proportion of the catalyst

is retained in each individual stage. In this manner, a catalyst activity gradient may be maintained throughout the system, varying from a maximum activity in the first stage to a minimum activity in the final stage. In this case, any required makeup 99.5-100% H₂SO₄ is added by line 84 to pass into the first stage and thus flow serially through the system at a slower rate than the flow of hydrocarbons through the system. The amount of fortified recycle acid introduced into subsequent stages from line 87 is then regulated primarily to control the water content in the subsequent stages, the organic content of the system acid progressively building up until acid discharged from the final stage is largely spent, whereby the bulk of the settled acid removed by line 73 can be discharged by line 74 to recovery. In that case, only sufficient recycle acid is returned by line 75 to provide for control of the water content as heretofore described.

As a further alternative, a portion of the fortified recycle acid mixed with isobutane recycle can be passed by valve-controlled line 94 to manifold 88, and this mixture distributed in independently controlled amounts between stages 2-5 by branch lines 89-92, the balance being passed by line 48 to the first stage 50. In this manner, the acid to hydrocarbon ratio in the various stages can be independently controlled and varied and the water content of the system acid also controlled, while the isobutane concentration can be maintained higher in the subsequent stages than where substantially all of the isobutane recycle is introduced into the first stage for serial flow through the system. This is of particular application where sufficient isobutane is available to maintain a high isobutane concentration in all stages.

In both Figs. 1 and 2, conventional operating conditions for sulfuric acid alkylation other than those specified above can be employed. For example, overall isobutane: olefin mol feed ratios of about 3:1 to 10:1 and preferably at least 5:1 may be used, together with an acid to hydrocarbon volume ratio in the reactor of around 1:1, a temperature of 30-60° F. and preferably about 40-50° F., and sufficient pressure to maintain the hydrocarbons in the liquid phase. However, the present invention is particularly useful in connection with the employment of higher acid to hydrocarbon ratios in the reaction mix, for example, a ratio of 45-90% by volume and preferably about 60-70% by volume. It is to be understood that the maximum acid to hydrocarbon ratio which can be tolerated for best results is a function of the mixing efficiency, and therefore depends upon the particular type of reactor used. The upper limit for best results with the Stratco reactor and the pump and time tank reactor appears to be about 65% by volume of acid; but higher ratios can be employed with other types of reactors having higher mixing efficiency.

While the present invention has been particularly described in connection with the alkylation of isobutane with a butylene, it is to be understood that it is applicable to the alkylation of any low-boiling isoparaffin or other paraffin hydrocarbon having a tertiary carbon atom in the molecule, with either a normally liquid or normally gaseous olefin. In place of isobutane, isopentane or isohexane may be employed. In place of a butylene, there may be employed propylene, pentylanes, hexylanes, other higher boiling mono-

meric olefins or certain selected fractions of cracked naphthas, olefin polymers such as di-isobutylene, tri-isobutylene, cross-polymers of isobutylene and normal butylene, such as codimer, and various mixed or non-selective polymers.

In place of olefins as the alkylating agent, various alkyl esters, such as the sulfates, chlorides, fluorides, etc. may be used. For example the present invention can be employed in a two-stage absorption-alkylation process, wherein the olefin is absorbed in acid in the first stage to produce the corresponding alkyl ester, and the ester either in solution in the absorbing acid or after separation therefrom as by isobutane or alkylate extraction, is then alkylated in the second stage in the presence of the system acid of low water content. Moreover, the present invention is particularly applicable to the alkylation of various aliphatic alcohols and ethers which are capable of forming olefins on reaction with the liberation of water, since the fortification of the acid recycle with fuming acid can be regulated to remove the water from the system acid substantially as rapidly as formed. Examples of such alcohols and ethers are tertiary butyl alcohol, isopropyl alcohol, butyl ether and the like. The expression "alkylating agent" is used herein throughout the description and claims to denote any of the above compounds which react with the isoparaffin in this alkylation reaction to produce alkylated hydrocarbons.

While contact times of the order of about 20-60 minutes are generally used in this alkylation process, it is to be understood that shorter contact times down to about 1-5 minutes may be employed particularly with the high acid to hydrocarbon ratios, thorough mixing of isobutane with recycle acid and makeup acid, and accelerated settling as by the aid of a centrifuge.

While the system acid in the reaction zone in accordance with the present invention can have a titratable acidity of about 88-94% (on an overall basis including water, ash and organic matter) for C₄ olefins, and about 85-90% or higher for C₅ olefins, it is found that this is not essential. In fact, the presence of a substantial content of organic material in the system acid may give improved results, apparently due to the fact that this increases the solubility of isobutane or other isoparaffin in the acid phase and thereby improves the selectivity of the alkylation reaction. For example, system acid having a titratable acidity of about 80-90% with a water content below 1% may be the preferred alkylating agent, and is definitely better than fresh white acid of 99-100% strength on an ash-free basis.

The use of system acid having an organic content in excess of 8% and a water content less than 4% and preferably less than 1% constitutes a distinct departure from prior practice in this art. Thus, in prior practice, where system acid was discharged from a continuous alkylation unit at a titratable acidity of around 88-90%, the water content was roughly equal to the organic content and generally ran in excess of 4%. Where spent acid from C₄ alkylation was then used for C₅ alkylation and reduced to a titratable acidity of about 85%, the system acid discharged from the C₅ alkylation generally had a content of not more than 7-8% organic matter and substantially in excess of 4% water. The above figures apply where predrying of the hydrocarbon feed was practiced. Where substantial water was introduced along with the hydrocarbon feed, the water content of the spent acid was even higher. Con-

sequently, it is seen that the overall titratable acidity of the system acid as formerly used is not a true measure of the alkylating activity of the acid catalyst, because of failure to differentiate between organic content and water content of that acid. The present invention includes the feature in continuous operation, with continuous discharge of a portion of the system acid and continuous makeup and fortification of recycle acid, of maintaining the organic content of the system acid above about 8% and preferably above about 10% by weight, while concomitantly maintaining the water content of the said system acid below 4% and preferably below 1% by weight.

Obviously many modifications and variations of the invention, as hereinbefore set forth, may be made without departing from the spirit and scope thereof, and therefore only such limitations should be imposed as are indicated in the appended claims.

We claim.

1. In the continuous alkylation of an isoparaffin with an alkylating agent in the presence of H₂SO₄ catalyst of alkylation strength in a reaction zone, wherein alkylation reaction products from the reaction zone are separated into hydrocarbon and catalyst phases, and a substantial proportion of the separated catalyst phase is recycled to the reaction zone and the balance is discharged, the improvement which comprises chilling the recycle acid stream to about 20-30° F., adding to the chilled recycle acid stream a stream of fuming sulfuric acid, promptly agitating the mixed streams to avoid localized overheating, controlling the strength and amount of fuming acid added in accordance with the water content of the recycle acid to thereby reduce the water content of the latter to less than 1% by weight while avoiding any residual free SO₃ in the fortified recycle stream, controlling the chilling of the recycle acid and the mixing of the fuming acid therewith so that the heat liberated does not raise the temperature of the agitated mixture above about 40° F., and returning the resultant fortified recycle acid to the reaction zone in an amount to maintain the system acid therein at a titratable acidity between 80 and 90%, with a water content of less than 4% by weight.

2. The method according to claim 1, wherein the water content of the system acid is maintained below about 1% by weight.

3. The method according to claim 1, wherein additional makeup 99.5-100% H₂SO₄ on an ash-free and organic-free basis is added to the reaction zone to provide for increased discharge of separated catalyst phase to recovery, to thereby prevent buildup of organic material in the system acid.

4. The method according to claim 1, wherein additional 96-99.5% H₂SO₄ on an ash-free and organic-free basis is added to the recycle acid stream prior to chilling of the latter in an amount proportioned to prevent organic buildup in the system acid, and the amount of fuming acid added is sufficient to compensate for the additional water present in the added 96-99.5% H₂SO₄ to thereby maintain the water content of the system acid below about 1% by weight.

5. The method according to claim 1, wherein the fuming acid is added to the recycle acid stream in stages, with chilling between stages.
